FIG. XVII.

UNITED STATES PATENT OFFICE.

CLARK SINTZ, OF PHILADELPHIA, PENNSYLVANIA, ASSIGNOR TO PENNSYLVANIA IRON WORKS COMPANY, OF PHILADELPHIA, PENNSYLVANIA, A CORPORATION OF PENNSYLVANIA.

VALVE MECHANISM FOR INTERNAL-COMBUSTION ENGINES.

No. 851,998.

Specification of Letters Patent.

Patented April 30, 1907.

Application filed March 21, 1905. Serial No. 261,342.

To all whom it may concern:

Be it known that I, CLARK SINTZ, of the city of Philadelphia, in the State of Pennsylvania, have invented certain new and useful Improvements in Valve Mechanism for Internal-Combustion Engines, whereof the following is a specification, reference being had to the accompanying drawings.

My improvements may be advantageously employed in internal combustion engines which are self starting and reversible in direction of rotation.

As hereinafter described my invention provides valve operating mechanism comprising a handle arranged to shift valve operating levers into engagement with different cams carried by a rotary cam shaft, to operate the inlet and exhaust valves in proper sequence for the different operations of the engine. For instance; in starting the engine, said valve levers may be shifted to engage cams for admitting and exhausting compressed air, and, after starting, said levers may be shifted to engage other cams for admitting air to be mixed with the charge of combustible.

In order to distinguish the air which is used *per se* as a motive fluid and the air which forms part of the combustible charge I shall hereinafter term the latter "fuel air."

Said mechanism is also so arranged that when the valve operating lever is shifted to start the engine in either direction the spark-timer in the igniter circuit will be automatically shifted to proper position to effect ignition at a period in the rotation of the crank shaft in which the consequent explosion will rotate said shaft in the desired direction.

The internal combustion engine hereinabove described is provided with a cam shaft having a plurality of valve operating cams; pivoted levers arranged to be shifted axially with respect to said cam shaft, to engage any selected cams on said shaft, or to be shifted out of engagement with said cams; a handle arranged to shift said pivoted levers; a spark-timer arranged to be partially rotated by the extreme movement of said handle, and, a hand lever connected to said spark-timer, whereby it may be independently shifted to vary the time of ignition with respect to the movement of the crank shaft.

My invention comprises the various novel

features of construction and arrangement hereinafter more definitely specified.

In the accompanying drawings, Figure I, is a front elevation of an internal combustion engine conveniently embodying my invention. Fig. II, is an elevation of the right hand end of said engine, as shown in Fig. I. Fig. III, is a fragmentary front elevation of the valve mechanism. Fig. IV, is a fragmentary sectional view, taken on the line IV, IV, in Figs. I, and III. Fig. V, is a central vertical sectional view taken through one of the engine cylinders, on the line V, V, in Fig. II. Fig. VI, is a plan view of the shifting device for said valve mechanism. Fig. VII, is a vertical sectional view of said shifting device, taken on the line VII, VII, in Fig. VI. Figs. VIII, to XVI, inclusive, are transverse sectional views of the cam shaft and the sleeves carried thereby, taken on the respective lines VIII, to XVI, inclusive in Fig. III. Fig. XVII, is a diagram of the electric igniter circuit.

In said figures,—the bed plate 1, is conveniently mounted on the beams 2, and provided with pairs of columns 4, 5, 6, and 7, which support the cylinders 8, 9, and 10, having the water jackets 11, surmounted by the water jacketed valve casings 12.

The crank shaft 13, having the cranks 14, is conveniently journaled in the frame 1, and provided at one end with the fly wheel 15, and at the other end with the eccentric 18, having the strap 19, operatively connected by the rod 20, to the air pump 21, which latter is arranged to deliver compressed air within the air reservoir 22, through the pipe 23. Said pipe 23, is also connected to the air inlet valves 25, arranged to admit compressed air to their respective cylinders 8, 9, and 10, to start and run the engine prior to the admission of the combustible charge, and said pipe 23, is conveniently controlled by the throttle valve 30. However, the combustible employed during normal operation of the engine may be liquid hydro-carbon, delivered by the pipe 32, to the vaporizer pumps 33, 34, and 35, which are supported by the brackets 38, and respectively connected to the cylinders 8, 9, and 10, through the valves 36, by the pipes 37.

As best shown in Fig. V, each of the valve

casings 12, comprises an air chamber 40, and an exhaust chamber 41. Each chamber 40, is supplied with air, for combustion, by a pipe 43, and connected with its respective cylinder through an air inlet port 44, which latter is arranged to be controlled by an air inlet valve 45. Each exhaust chamber 41, is in communication with its respective cylinder through an exhaust port 47, which 10 is arranged to be controlled by an exhaust valve 48, and opens into the exhaust pipe 49.

The valves 45, and 48, are respectively provided with valve stems 50, and 51, extending exterior to their casings 12, through 15 the flanged bushings 52, and having adjustable nuts 53, between which latter and the flanges of said bushing 52, conical coiled springs 55, are held under compression, and are arranged to normally retain the valves 45, 20 and 48, on their respective seats 56, and 57.

The valves 25, 45, and 48, are arranged to be controlled by the cam shaft 60, which is driven by the crank shaft 13, through the train of gears 61, 62, and 63, at a speed of 25 one half that of said shaft 13.

The cam sleeves 65, 66, and 67, are keyed on said shaft 60; adjacent to the respective cylinders 8, 9, and 10, and the sleeves 65, and 67, are each provided with respective 30 counterpart fuel air inlet cams 70, compressed air inlet cams 72, and exhaust cams 74, and 75; which latter are notched as indicated at 76, in Fig. III. The sleeve 66, is provided with the fuel air inlet cams 78, 35 the compressed air inlet cams 79, and the exhaust cams 80, and 81, which differ slightly from the similar cams of the sleeves 65, and 67.

The cam sleeves 65, 66, and 67, are arranged to be traversed by respective sets of 40 rollers 90, 91, and 92, journaled in individual bifurcated shifting levers 93, which comprise horizontal webs 94, and hubs 95, and which are mounted to oscillate on their longitudinally movable shifting shaft 96, and are compelled to move axially with said shaft 96, by 45 the collars 97, secured thereto on either side of each set of the shifting levers.

The shaft 96, is mounted for axial movement in the bearings 100, carried by the columns 4, 5, 6, and 7, and is arranged to simultaneously shift all of the levers 93, and their respective rollers 90, 91, and 92, in an axial direction with respect to the cam shaft 60, so as to present said rollers in alinement with 50 any selected cams on the cam sleeves to operate their respective valves. Said shifting levers 93, are uplifted by the rotation of the aforesaid cams on the cam sleeves beneath the rollers 90, 91, and 92, and impart their 55 motion to the levers 103, 104, and 105, which are provided with rollers 106, which rest upon the webs 94, of the levers 93. Said levers 103, 104, and 105, comprise hubs 107, 60 mounted to oscillate on the stationary shaft 108, supported by the brackets 109, on the 65

columns 4, 5, 6, and 7, as shown in Fig. III. Said levers 103, 104, and 105, are adjustable in screw threaded engagement with the respective valve rods 110, 111, and 112. Said rods 110, and 112, are connected to the respective levers 114, and 115, which are fulcrumed in the brackets 116, supported by the valve casings 12, and said levers are respectively provided with the adjustable set screws 117, and 118, secured by the locked nuts 119, and 120, and arranged to engage the respective valve stems 50, and 51, to alternately open the air inlet port 44, and the exhaust port 47, to admit air into the combustion chambers 121, (which are at the top 70 of the cylinders, as indicated in Fig. V,) and to exhaust said cylinders. The cam shaft 60, is also provided with cams 125, 126, and 127, arranged to deliver hydrocarbon gas into the cylinders, by depressing the rollers 85 128, and plungers 129, of the vaporizer pumps 33, 34, and 35; said plungers being normally uplifted by the coiled springs 130. The rate of delivery of said gas to the engine cylinders may be varied or terminated by 90 withdrawing said plungers from the paths of rotation of said cams, such control being effected by shifting the hand lever 132, on the vertical rod 133, which is supported in the brackets 134. Said rod is provided with the 95 lever 135, in engagement with the slide rod 137, which is arranged to slide horizontally in the guides 136, on the brackets 38, and present its wedge cams 138, against the cam lugs 139, on the levers 140, which latter are 100 fulcrumed on the brackets 38, and connected to said vaporizer plungers 129.

It is to be understood that the speed of the engine is varied in correspondence with the aforesaid variation in the supply of the gas, 105 by movement of said hand lever 132, which shifts the wedge cams 138, to rock the levers 140, and thereby depress the plungers 129, so that the successive revolutions of the cams 125, 126 and 127, will not reciprocate 110 the plungers 129, to their maximum extent. By limiting the throw of the plunger 129, it may be readily seen that the supply of hydrocarbon pumped thereby is limited accordingly. 115

The lever shifting shaft 96, is provided with the collars 145, arranged to form the groove 146, and said shaft is arranged to be shifted by the operating handle 150, which is secured to the upper end of the vertical 120 shaft 151. The lower end of said shaft is provided with a pair of levers 153, having opposed lugs 154, extending into said groove 146. Said shaft 151, is rotatably supported in the sleeve 155, which is secured to the air pump 21, by the brackets 157. Said sleeve 155, supports the quadrant 160, having the notches 161, to 167, inclusive, beneath the operating handle 150, which is provided with the pawl 170, fulcrumed at 171, and arranged 130

to engage said notches 161, to 167, which correspond to the different positions of the lever shifting shaft 96.

The cam shaft 60, is provided with the contact arm 175, arranged to strike the contact points 176, of the spark - timer 178, having the binding posts 179, to which are attached the wires 180, extending from the spark plugs 185. As best shown in Fig. XVII, the circuit 5 includes the spark coil 182, the battery 183, and the switch 184. Said spark-timer 178, is normally stationary while the engine is running, but may be partially rotated to change the time of ignition with respect to the rotation of the crank shaft, by movement of the link 187, which connects with the lever 188, having the handle 189. Said lever 188, is pivoted to the frame 190, which is secured to the quadrant 160, and includes the quadrant 191, and said lever is arranged to be frictionally engaged in adjusted position, by the 15 clamping piece 192, held and adjusted by the bolt 193, and its nut 194, as best shown in Fig. VI.

When the engine is operating by internal combustion, it is necessary to advance the time of ignition with respect to the rotation of the crank shaft, to attain a high speed, and this is effected by partially rotating the spark-timer 178, by its shifting lever 188, which is then retained in any desired position of adjustment, by the frictional contact of its clamping piece 192, against the quadrant 191.

If the engine is running at its highest speed, the spark-timer is so set that the sparks are produced by the igniters before the crank reaches its upper dead center, and if the engine be stopped while the spark-timer is so set, and any attempt be made to again start it, it would tend to rotate in the reverse direction. To prevent such reversal, the spark-timer shifting lever 188, is provided with a buffer lever 195, and is connected by the link 196, to the buffer lever 197, also pivoted on the frame 190. Said buffer levers are arranged to be engaged by the lug 198, depending from the operating handle 150, so that the movement of said handle to either of its extreme positions to start the engine 40 effects the adjustment of the spark-timer 178, to such position that the spark will occur after the crank has passed its upper dead center.

It may be here noted, that when the engine is operated by internal combustion it is of the four-cycle type, and that the crank shaft 13, makes two revolutions for each revolution of the cam shaft 60. Therefore, it is necessary to provide said cam shaft 60, with diametrically opposite counterpart cams to engage the valves of the engine which are employed to initially operate it by compressed air, for the engine then operates as a two-cycle engine, each piston being given an impulse at each out stroke.

The cylinders and valve casings above described are arranged to be cooled by water circulated therethrough by the pump 200, comprising the pump piston rod 201, connected to the lever 202, which is fulcrumed 70 at 204, and connected to the rod 20, by the link 205, arranged to force water through the inlet pipe 207, into the water jacket 11, through the short nipple 208, into the water jacket 16, and out through the outlet pipe 75 210.

As shown in the drawings, the engine is in its idle position, and by the shifting of the handle 150, to the left or right (with reference to Fig. I,) the valve operating levers 93, 80 are set in a position to start to rotate the engine respectively forward or backward. If it is desired to start the engine in the forward direction, the handle 150, is shifted to its extreme left hand position (with reference to 85 Fig. I) until its pawl 170, engages the notch 164, in the quadrant 160, in which position the lug 198, will engage and rock the buffer lever 197, and lever 188, to set the spark-timer 178, in such relation to the cranks 14, 90 as to rotate the engine in a forward direction, by internal combustion, after its initial operation by compressed air.

The rollers 91, which are arranged to operate the compressed air inlet valves 25, of the cylinders 8, and 10, are then in alinement with the forward compressed air inlet cams 72, of the sleeves 65, and 67, and the roller 91, which is arranged to operate the compressed air inlet valve 25, of the cylinder 9, is 95 then in alinement with the forward compressed air inlet cams 79, of the sleeve 66; while the rollers 92, which are arranged to operate the exhaust valves 48, of the cylinders 8, and 10, are in alinement with the forward exhaust cams 74, and 75, of the sleeves 65, and 67, and, the roller 92, which is arranged to operate the exhaust valve 48, of the cylinder 9, is in alinement with the exhaust cams 80, and 81, of the sleeve 66. The 105 throttle valve 30, is then opened to the three cylinders 8, 9, and 10, which operate by compressed air admitted successively to said cylinders by the opening of their respective valves 25.

After the engine has been started, the operating handle 150, is shifted to the right (with reference to Fig. I,) until its pawl 170, engages the notch 163, which shifts the rollers 91, of the end cylinders 8, and 10, out of 110 alinement with the compressed air inlet cams 72, and presents the rollers 90, (which are arranged to operate the air inlet valves 45, for combustion) in alinement with the forward air inlet cams 70, of the sleeves 65, and 67. The rollers 92, which are arranged to operate the exhaust valves 48, being shifted to such a position as to be engaged by the exhaust cams 74, and 75, in registry with the notches 76; are arranged to exhaust said cyl- 115 120 125 130

inders 8, and 10, later, when operated by internal combustion, than when operated by compressed air. The vaporizer pumps are then adjusted to deliver the gas at the desired rate, by shifting the lever 132, and rod 137, to the corresponding extent.

The compressed air inlet cams 79, are longer, and the air inlet cams 78, shorter, on the sleeve 66, than the similar cams 72, and 70, on the sleeves 65, and 67; so that the central cylinder 9, continues to operate as a compressed air engine until the end cylinders 8, and 10, have been completely cleared of air, and are in condition to maintain the proper speed. The handle 150, is then shifted until its pawl 170, engages the notch 162, which shifts the rollers 90, 91, and 92, into alignment with the air inlet and exhaust cams to operate all of the cylinders by internal combustion and the throttle valve 30, is then closed. The time of ignition may then be advanced to increase the speed as desired, by shifting the lever 188, to adjust the spark-timer 178.

When it is desired to stop the engine the switch 184, is shifted as shown in dotted lines in Fig. XVII, to break the circuit, and the handle 150, being then shifted to its central position, as shown in the drawings, the pawl 170, will engage the notch 161, and the rollers 90, 91, and 92, will be disposed on the cam sleeves 65, 66, and 67, in such relation as to be incapable of operating in proper sequence to rotate the engine.

If it is desired to operate the engine in a reverse direction, the handle 150, is shifted to the right (with reference to Fig. I), until its pawl 170, engages the notch 167, and is then shifted successively to the notches 166, and 165, when the engine will be in position for running backward at full speed, by internal combustion.

I do not desire to limit myself to the precise details of construction and arrangement herein set forth, as it is obvious that various modifications may be made therein without departing from the essential features of my invention.

I claim:

1. In an internal combustion engine, the combination with a series of three cylinders; of starting mechanism comprising means to first direct a supply of compressed air *per se* to each of said cylinders; then shut off the supply of compressed air from the opposite end cylinders and admit a combustion charge into said end cylinders, while admitting compressed air *per se* to the intermediate cylinder; then shut off the supply of compressed air to said intermediate cylinder and supply all of the cylinders with a combustion charge, substantially as set forth.

2. In an internal combustion engine, the combination with a series of cylinders; of starting mechanism comprising means to first

direct a supply of compressed air *per se* to each of said cylinders, at alternate strokes of their pistons; means to contemporaneously terminate the supply of compressed air to selected cylinders in the series and to admit a combustion charge to said selected cylinders at each fourth stroke of said pistons, and means to terminate the supply of compressed air and to admit a combustion charge to all of said cylinders at each fourth stroke of their pistons, substantially as set forth. 70 75

3. In an internal combustion engine, comprising a cylinder provided with inlet and exhaust valves; the combination with a rotary cam shaft having a plurality of cams; of a slide rod in parallel relation to said cam shaft; a series of valve operating levers pivoted to independently oscillate on said rod, and arranged to be contemporaneously shifted axially therewith; a roller carried by each of said levers arranged to engage selected cams on said shaft; a stationary shaft; levers pivoted on said stationary shaft and provided with rollers arranged to engage said valve shifting levers; centrally pivoted levers, adjacent to 90 said valves, valve rods adjustably connected to the levers on the stationary shaft and pivotally connected to said centrally pivoted levers, which latter are arranged to actuate their respective valves in accordance with 95 the movement of said cams and the rollers coöperating therewith, substantially as set forth.

4. In an internal combustion engine, comprising a cylinder provided with inlet and exhaust valves, the combination with a rotary cam shaft having a plurality of cams; of a slide rod in parallel relation to said cam shaft; a series of valve operating levers pivoted to independently oscillate on said rod; and arranged to be contemporaneously shifted axially therewith; a stationary shaft; levers pivoted on said stationary shaft and provided with rollers arranged to engage said valve operating levers; connections between 110 said pivoted levers and said valves; a vertical shaft connected to shift said rod axially; a handle for said vertical shaft; and means cooperative with said handle whereby the successive positions of said rod are determined, 115 substantially as set forth.

5. In an internal combustion engine, comprising a cylinder provided with inlet and exhaust valves; the combination with a rotary cam shaft having a plurality of cams; of a slide rod in parallel relation to said cam shaft; a series of valve operating levers pivoted to independently oscillate on said rod and arranged to be contemporaneously shifted therewith; a stationary shaft; levers pivoted on said stationary shaft and provided with rollers arranged to engage said valve operating levers; connections between said pivoted levers and said valves; a vertical shaft connected to shift said rod axially; a 125 130

handle for said vertical shaft; a pawl on said handle; and a quadrant having notches therein arranged to be engaged by said pawl, whereby the extent of the successive axial movements of said rod is determined, substantially as set forth.

6. In an internal combustion engine, comprising a cylinder provided with inlet and exhaust valves; the combination with a rotary cam shaft having a plurality of cams; of a slide rod in parallel relation to said cam shaft; a series of valve operating levers pivoted to independently oscillate on said rod, and arranged to be contemporaneously shifted axially therewith; a vertical shaft connected to shift said rod axially; a handle for said vertical shaft; a spark-timer mounted on the cam shaft, a contact arm carried by said

shaft in operative relation to said spark-timer; buffer levers pivoted at each side of said handle; a link connecting said levers; a link connecting one of said levers and said spark-timer; means carried by said handle arranged to engage in its extreme position one or the other of said buffer levers to set 20 said spark-timer in accordance with the forward or reverse direction in which the engine is to be operated, substantially as set forth.

In testimony whereof, I have hereunto signed my name, at Philadelphia, Pennsylvania, this 14th day of March, 1905.

CLARK SINTZ.
